W. O. ERBES

SOUND RESONATOR

Filed Feb. 7, 1923

INVENTOR
WILLIAM O. ERBES
BY *J. S. Rivers*
ATTORNEY

UNITED STATES PATENT OFFICE.

WILLIAM O. ERBES, OF EVERETT, WASHINGTON.

SOUND RESONATOR.

Application filed February 7, 1923. Serial No. 617,528.

To all whom it may concern:

Be it known that I, WILLIAM O. ERBES, a citizen of the United States, residing at Everett, in the county of Snohomish and State of Washington, have invented a new and useful Sound Resonator, of which the following is a specification.

My invention has particular reference to improvements in devices for amplifying and 10 modifying sounds produced mechanically or by the human voice, and is designed to take the place of and to set forth an improved construction on the invention disclosed in my application No. 479,375, for sound resonator for phonographs, filed by me in the United States Patent Office on June 21st, 1921.

The objects of my invention are, to provide a device constructed entirely of wood, 20 and having a sound chamber and sounding board, to be used in connection with talking machines, for radio receiving and transmitting, or with the human voice, adapted to amplify and enrich the tones 25 carried thereby; to provide a construction which in effect will simulate the resonant properties of a violin; to provide means whereby the human voice can be amplified and rendered more resonant, for public 30 speaking, for making announcements, or in connection with music simultaneously conveyed by the device; to provide a flexible connection for the tone arm and reproducer of a phonograph, or the like, with its disc 35 actuating mechanism, which will improve the quality of the tones produced and practically do away with what is termed "the scratch"; and, to provide an auxiliary sound outlet by means of which extraneous sounds 40 are eliminated and the tones rendered full, rounded and more harmonious.

In the accompanying drawing—

Figure 1 is a view in perspective illustrating how the device is connected up with a 45 talking machine, and including a mouthpiece for the resonator, a stand for the disc actuating mechanism of said machine, and a broken off section of a supporting table for the assembly.

Fig. 2, a central longitudinal section of 50 the resonator complete, drawn on the line

2—2 of Fig. 1, said mouthpiece having been removed.

Fig. 3, a plan view of the sound chamber, indicating the sounding board, its means of attachment to the chamber, and the supports for the amplifier in place and extending upwardly through openings in the top of the chamber.

This resonator is a structure composed 60 entirely of wood; a select close-grained spruce, koa wood, mahogany or any other wood possessing sufficient vibratory qualities being suitable. To fully realize the advantages of this wood construction in imparting resonance to the sounds conveyed 65 through the resonator, the parts should be so cut and assembled as to permit the grain of the wood to extend longitudinally, wherever possible, as indicated in Fig. 1. For 70 the same purposes the device, in its preferred form, is pegged and glued together—the use of metal being eliminated.

Referring more particularly to the drawing, the sound chamber 1, a rectangular 75 structure as shown, carries within it a sounding board 2, frustro-conical in outline, which is secured to the inner periphery of the top by a single central support 3. Three supports 4, rectangular in cross-section, are 80 connected with said board and extend upwardly through openings 5 in the top of the chamber, Fig. 3, and are spaced away therefrom. Said supports are also secured to the amplifier, as indicated in Fig. 2, and 85 provide, in connection with the sounding board, a flexible connection therefor.

This flexibility is attained by reason of the fact that the sounding board 2 is held 90 in a dependent position within the sound chamber, about centrally thereof and spaced away from the sides, its single means of attachment to the chamber being the medial support 3, a block pegged and glued to the sounding board and the top as indicated in 95 Fig. 2. The three supports connecting the amplifier with the sounding board are secured in place in a similar manner, as shown in the last-named figure. The means of attachment just described, together with 100 the resilient properties of the material used, impart the necessary flexibility to this con-

nection; more apparent at the reduced end of the sounding board, where it is particularly needed. The function of this feature will be described hereafter.

- 5 The amplifier is provided with a hollow flared portion 6, which obviously is the primary outlet for sounds to be conveyed thereby. A hollow neck portion 7 communicates with said flared portion, is fixedly 10 attached thereto, and terminates at its free end in an auxiliary sound outlet 8.

An upstanding sound conduit 9, disposed between said portions, is secured to and communicates therewith. It is provided 15 with an angular section 10, adapted to direct the sound waves toward the flared end, and at the same time afford a construction which is economical in cost and permits the parts to be assembled so that the grain 20 of the wood will extend lengthwise, in aid of resonancy. The conduit terminates at its free end in a socket 11 to receive and carry the tone arm and reproducer of a talking machine.

- 25 The auxiliary sound outlet 8, in addition to the functions hereinafter described, serves as a modulating vent; it gives free action to the sound waves, and takes away any echo that might otherwise exist. Its harmonious 30 effect upon the tones can be readily ascertained by placing or removing the hand on or from this outlet when the resonator is in action.

In Fig. 1, which illustrates the device as 35 connected up with a phonograph, or the like, and in operative position for vocal accompaniment therewith, 20 denotes a table, shown in broken sections, for supporting the entire device and connections, 21 a stand in 40 which the disc actuating mechanism is mounted, 22 a crank for winding the same, 23 a tone arm and reproducer seated on said sound conduit, and 24 a mouthpiece for voicing purposes.

- 45 In utilizing the resonator, in connection with a phonograph as shown in Fig. 1, the tone arm, carrying the reproducer, is mounted in the socket 11 in the free end of the conduit. This conduit, located as it is rearwardly of the flared portion and adjacent 50 to the single support connected with the smaller end of the sounding board, is in a position to take advantage of the flexibility imparted to the amplifier by the natural resiliency of the wood and the construction heretofore described. It affords a seat having just enough flexibility to produce the proper tones from the instrument, and at 55 the same time lessen wear on the needles and records used and eliminate the scratching sounds often produced when the tone arm is mounted more rigidly.

The detachable mouthpiece 24 is useful when it is desired to sing or whistle an accompaniment to instrumental music played

by the phonograph, or to be spoken into when using the resonator for making announcements or in public speaking. Or, for the same purposes, by removing the mouthpiece, an electric amplifier with a telephone 70 connection can be inserted in the auxiliary sound outlet 8, thereby imparting added resonance and volume to the tones. Said amplifier may also be utilized in receiving or sending sounds by radio; the mouthpiece 75 being dispensed with, and the amplifier mounted in the outlet last referred to.

As the device is sensitive both for the reception and transmission of sounds it may be used, when mounted in a convenient place, 80 by night watchmen in detecting unusual sounds. By placing the ear to the auxiliary sound outlet, either with or without the mouthpiece, said sounds become more audible and distinct.

The features heretofore mentioned unite in producing, in connection with the different means described for their employment, not only amplification of tone but modification as well, in that the sounds conveyed are 90 rendered more vibrant and sonorous, and harsh sounds produced mechanically are either eliminated or reduced to the minimum.

I claim:

1. In a device of the class described, an amplifier comprising a hollow body having a horizontal lower portion, one end defining an outwardly and upwardly flared portion, the other end a neck portion provided with a sound outlet, and a hollow upstanding sound conduit disposed between said portions and communicating therewith, terminating at its free end in a socket adapted to carry a tone arm of a talking machine.

2. In a device of the class described, an amplifier made of wood the grain of which is longitudinally disposed, having a hollow body provided with a horizontal lower portion, one end defining an outwardly and upwardly flared portion, the other end a straight neck portion terminating in a sound outlet, a hollow angular member rectangular in cross-section disposed between said flared and neck portions and communicating therewith, said member being inclined toward the flared portion, and a hollow vertically extending member rectangular in cross-section communicating with the angular member, and provided at its free end with a seat for 105 a tone arm of a talking machine.

3. In a device of the class described, a sound chamber provided with a sounding board frustro-conical in outline disposed within the chamber and spaced from the sides thereof, a central support for the board securing the same to the inner periphery of the top of the chamber and spacing the board away therefrom, a plurality of upstanding supports secured to the upper 115 120 125 130

surface of the board and adjacent each end thereof, extending above and spaced away from openings in the top of the chamber, affording a flexible connection for an amplifier adapted to be mounted on said last-named supports.

4. In a device of the class described having a sound chamber, a sounding board

mounted therein, a plurality of supports secured to the board and extending through and spaced away from the top of the chamber, adapted to provide, in co-operation with the board, a flexible mounting for an amplifier, and an amplifier mounted on the supports.

WILLIAM O. ERBES.
